CLAIM

The ornamental design for an aquarium scraper, as shown and described.

DESCRIPTION

FIG. 1 is a front, right and top perspective view of an aquarium scraper, showing my new design;

FIG. 2 is a rear, left and bottom perspective view thereof; FIG. 3 is a rear, left and bottom perspective view of the aquarium scraper in a contraction state;

FIG. 4 is a front, right and top perspective view of the aquarium scraper in a detached state;

FIG. 5 is a front view thereof;

FIG. 6 is a rear view thereof;

FIG. 7 is a left side view thereof;

FIG. 8 is a right side view thereof;

FIG. 9 is an enlarged top plan view thereof;

FIG. 10 is an enlarged bottom plan view thereof; and,

FIG. 11 is an enlarged view of portion 11 shown in FIG. 2. The broken lines depict portions of the aquarium scraper station and form no part of the claimed design.

1 Claim, 11 Drawing Sheets
